UNITED STATES PATENT OFFICE.

JOSEPH HOLLE, OF NEWARK, NEW JERSEY, ASSIGNOR TO McCORD MANUFACTURING COMPANY, INC., OF DETROIT, MICHIGAN, A CORPORATION OF NEW YORK.

GASKET.

1,387,648.

Specification of Letters Patent. Patented Aug. 16, 1921.

Application filed October 4, 1920. Serial No. 414,485.

To all whom it may concern:

Be it known that I, JOSEPH HOLLE, a citizen of the United States, residing at Newark, in the county of Essex and State of New Jersey, have invented new and useful Improvements in Gaskets, of which the following is a specification.

This invention relates to gaskets, and more particularly to gaskets of the kind disclosed in my copending application, Serial No. 319,274, filed August 22nd, 1919. The gasket disclosed therein is made of sheet metal shaped to provide two tubular guide flanges on opposite sides of an outwardly extending, annular section forming a chamber to receive and retain a ring of fibrous material, such as asbestos.

The object of the present invention is to reinforce or strengthen at least one of said tubular guide flanges against being bent inward or otherwise displaced when such flange strikes against the edge of the hole or port in the part into which such flange is inserted in the application of the gasket in its position of use.

The invention consists further in the matters hereinafter described and more particularly pointed out in the appended claims.

In the accompanying drawings—

Figure 1 is a side elevational view of a gasket embodying the features of my invention;

Fig. 2 is an enlarged diametrical sectional view taken on line 2—2 of Fig. 1; and

Fig. 3 is a horizontal sectional view taken through that portion of the wall of an engine casting provided with the ports for the intake and exhaust manifolds, respectively, and showing gaskets of my invention between such parts at the joints thereof.

As shown in the drawings, the gasket is annular and has a body portion made of sheet metal, such as copper, and formed to provide two tubular guide flanges 1 and 2, substantially in alignment and on opposite sides of an outwardly extending annular section 3 forming an annular chamber to receive and retain a ring 4 of fibrous material, such as asbestos.

To reinforce or strengthen one of the tubular guide flanges so as to prevent it from being bent over or inward or otherwise displaced out of its proper guiding position in the insertion of that guide into a port hole or the like, I provide a reinforcing member

made of sheet metal and annular in form. This member, in the form shown in the drawings, has two integral flanges 5 and 6, arranged substantially at right-angles to each other, and when applied to the gasket 60 has its base flange 5 inserted into the chamber formed by the section 3 between the fiber ring 4 and the adjacent wall of the section 3. The other flange 6 is substantially 65 in alignment with the tubular guide 1 and extends away from the same across the inner edge of the ring 4 and along the inner surface of the tubular guide flange 2. The flange 6 has a diameter substantially equal to the inside diameter of the guide 2, so that 70 the flange 6 has a tight fit against the guide 2 on the inside thereof. The height or length of the flange 6 is equal to that of the same dimension of the guide 2 and the thickness of the ring 4, and the flange has its 75 outer edge terminating at the outer edge of the guide 2. The flange 6 is thus a part of the guide 2 and makes it have a multiple thickness of sheet metal, with the result that the guide 2 is strengthened to that extent. 80 The flange 5 seating against a wall of the section 3 and held in contact therewith by the fiber ring 4, prevents the flange 6 from being bent inwardly and thus supports the guide flange 2 and prevents it from being 85 bent inward. This, therefore, supports the guide flange 2 in proper guiding position and prevents it from being bent inward on striking against the port into which it is inserted. Moreover, the outer edge of the 90 guide flange 2 being formed of a multiple thickness of metal prevents curling or bending over of that edge.

In Fig. 3, I have shown an intake manifold 7 and an exhaust manifold 8, these registering with the ports 9 and 10, respectively, in the wall 11 of the engine casing, when the manifolds are in use and clamped against said wall. The gasket shown and described is used at the joint between each manifold 95 and its cylinder port. When applying the manifold against the cylinder wall, a gasket is first applied to the manifold before it is applied to the engine. In applying the gasket, its tubular guide flange 1 is inserted 100 into the open end of the manifold until stopped by the section 3 contacting with the end of the manifold. This connects the gasket with the manifold, or, in other words, the manifold carries the gasket. The mani- 110

fold is then applied to the engine, the guide flange 2 of the gasket projecting outward from the manifold and inserted into the cylinder port to guide the manifold into position over the port. It is in inserting the guide flange 2 into the cylinder port that the flange is likely to strike the edge of the port or against the wall 11 about the port, and, being reinforced or strengthened by the flange 6, the guide flange 2 is prevented from being bent inward or otherwise displaced on striking such parts. Manifestly, the use of the gasket is not limited to one application; that is, the guide flange 2 is held against bending and thus is maintained in proper condition and enables the gasket to be used over and over again and thus does not have to be thrown away after one installation.

The body of the gasket, as shown herein, follows the construction in my copending application; that is, the tubular guide flanges 1 and 2 are made separate with the guide 1 having an integral flange bent outward and inward to form a chamber for the fiber ring 4, and the other guide flange 2 having an integral flange bent outward to extend under the adjacent wall of the chamber, as shown in Fig. 2, although of course I do not wish to be limited in my present invention to this exact formation of gasket. Furthermore, the reinforcing member of my present invention may be variously changed and modified without departing from the spirit and scope of my invention.

35 I claim as my invention:

1. A gasket of the character described,

comprising a metallic body portion formed to provide two tubular guide flanges extending in opposite directions on opposite sides of an outwardly extending annular section 40 forming a chamber to receive and retain a ring of fibrous material, and means for holding one of said guide flanges against bending inward.

2. A gasket of the character described, 45 comprising a metallic body portion formed to provide two tubular guide flanges extending in opposite directions on opposite sides of an outwardly extending annular section forming a chamber to receive and retain a 50 ring of fibrous material, and a metallic annular member inside of one of said guide flanges and fitting against the same to hold said flange against bending inward.

3. A gasket of the character described, 55 comprising a metallic body portion formed to provide two tubular guide flanges extending in opposite directions on opposite sides of an outwardly extending annular section forming a chamber to receive and retain a 60 ring of fibrous material, and a strengthening member inside of one of said guide flanges and having two flanges, one extending into said chamber under the ring thereon and the other extending across the inner edge of the 65 ring and fitting against the inside of the last mentioned guide flange.

In testimony that I claim the foregoing as my invention, I affix my signature this 27th day of September, A. D. 1920.

JOSEPH HOLLE.
